MORTON C. HUTCHINSON, OF WOODBURY, NEW JERSEY, ASSIGNOR TO CHICAGO PNEUMATIC TOOL COMPANY, OF CHICAGO, ILLINOIS, A CORPORATION OF NEW JERSEY.

PNEUMATIC-TOOL HANDLE.

1,315,554.

Specification of Letters Patent.

Patented Sept. 9, 1919.

Application filed August 25, 1916. Serial No. 116,767.

To all whom it may concern:

Be it known that I, MORTON C. HUTCHINSON, a citizen of the United States, residing at Woodbury, in the county of Gloucester, State of New Jersey, have invented a new and useful Pneumatic-Tool Handle, of which the following is a specification.

My invention relates to the grasping handle of a pneumatic tool of the type generally employed for riveting and chipping, and analogous uses, and consists more especially of a novel construction of the valvular mechanism therein, particularly the bushing, valve and their adjuncts, whereby the flow of the compressed air or other motive fluid under pressure from the supply hose to the tool cylinder is controlled through the medium of a manually operated lever or other device mounted on the upper or other portion of the grasping handle.

In pneumatic tools of the prior art as generally commercially constructed, it has heretofore commonly been the custom to locate in the grasping or other portion of the pneumatic tool handle, a valve bushing having a bore therethrough of uniform diameter and to locate within said bushing a sliding throttle valve composed of two pistons of uniform diameter joined by a neck, which pistons control the flow of the motive fluid through the handle to the valve and piston of the pneumatic tool.

While this construction may have the advantage of being cheaply manufactured, since it may be somewhat cheaper to manufacture a bushing having its internal bore of the same diameter throughout and it may also be somewhat cheaper to construct a throttle valve with two pistons of uniform diameter, I have found that in these tools, which are frequently subjected to considerable abuse by the workmen, a throttle valve of this character soon becomes leaky and is less efficient than a throttle valve of my novel construction hereinafter referred to, wherein a valve stem having a ground piston thereon is employed in conjunction with a lower valve body preferably of greater diameter, which has a relatively looser fit in its bushing to enable a limited volume of live air at reduced pressure to constantly act on the bottom of the valve to force the latter upwardly, the valve seat in the bushing being intermediate said piston and valve body, and said valve body seating upwardly

and being always pressed upwardly toward and against its seat by the pressure of the motive fluid, the construction being such that not only is the life of the throttle valve and bushing greatly prolonged, and leakage of the compressed air prevented, but the valve in the handle will remain effectively seated under normal conditions of non-use or when the pneumatic tool is inoperative, any leakage or waste of the compressed air being entirely and absolutely obviated, this item of leakage of the compressed air or other motive fluid in large industrial plants such as ship-yards, boiler shops and the like where a number of pneumatic tools of this general character are employed being one of considerable importance.

It further consists of other novel features of construction, all as will be hereinafter fully set forth.

For the purpose of illustrating my invention, I have shown in the accompanying drawings certain forms thereof which are at present preferred by me, since the same will give in practice satisfactory and reliable results, although it is to be understood that the various instrumentalities of which my invention consists can be variously arranged and organized and that my invention is not limited to the precise arrangement and organization of these instrumentalities as herein shown and described.

The figure represents a vertical sectional view of a pneumatic tool handle, embodying my invention, the valve and its adjuncts being shown in elevation.

Referring to the drawings:—

1 designates a pneumatic tool handle having the inlet 2, containing the nipple 3, for the attachment of the compressed air hose, 95 said air or other fluid pressure passing through the chamber 4 and inlet ports 5 and outlet ports 6 of the valve bushing 7 to the pressure supply duct 8, located in the grasping or other portion 9 of the handle 1, 100 and being conducted therefrom to the tool cylinder 10, which may be of any suitable construction. The valve bushing may be secured in the handle by a driving fit or otherwise.

12 designates a valve seat in the bushing 7 located intermediately of the inlet ports 5 and outlet ports 6, against which the throttle valve body 13 seats in an upward direction, said valve having the beveled portion 14, 110

which acts as the valve proper, the latter being normally at all times pressed upwardly against its seat by the pressure of the motive fluid.

5 18 designates the upwardly extending valve stem, which is shown as being integral with the valve 13, said stem carrying the piston 19, which is of less diameter than the valve body 13 and ground to nicely and exactly fit the bore 20 of the bushing 7, while the valve body 13 should have about .005 play in the lower portion of its bushing, it being only essential that the valve 14 fit accurately upon its seat 12. The object in 10 making the valve body 13 with about .005 play is to enable a limited quantity of the motive fluid to flow through the port 5 around the valve 13 and be wiredrawn down into the valve chamber 29 so that the valve proper 14 will be always tightly seated, so as to prevent any leakage of the motive fluid when the tool is not in use. The upper extremity 21 of the valve stem is in contact with and depressed by the cam 22 of 15 the manually operated valve lever 23, which is composed of thin metal and pivotally mounted at 24 in the narrow slit 25 in the upper or other portion of the grasping handle, said valve lever being provided at 20 its lower portion with the extension 26, which is normally in contact with the shoulder 27 and at its upper portion with the thumb piece 28, whereby a depression of said thumb piece will tend to unseat the valve 25 14 from its seat 12, said valve being normally held seated at all times by a limited quantity of motive fluid wiredrawn to below the bottom of said valve to seat the same upwardly at a pressure reduced from the initial pressure of the incoming motive fluid through the nipple 3.

It will be apparent that while I have shown my device in the present instance as applicable to the well-known "Boyer" type 45 of grasping handle wherein the pressure supply duct is led through the grasping portion of the handle, my invention is equally applicable to other forms of pneumatic tool handles, wherein the valve proper 50 as well as the pressure supply duct are located wholly outside of the grasping portion of the handle, it being a common right to conduct the motive fluid to the pneumatic tool cylinder either within or without the 55 grasping portion of the pneumatic tool handle.

It will be seen from the foregoing that by making the piston 19 of a ground fit, there will be no improper leakage of the motive 60 fluid when the valve body 13 is in its depressed position, and when the valve is closed, which is the position the parts assume when the tool is not in use, there is no opportunity for leakage under any conditions. The valve body 13 can obviously be

cheaply manufactured, it only being essential that the valve proper 14 accurately fit its seat 12.

As already explained, in the old style of throttle valve where the bushing has a bore 70 of uniform diameter and the valve pistons are of uniform diameter, in a few months' time owing to the wear between said pistons and bushing, there is a constant leakage of compressed air which it is especially desirable to prevent on account of the expense and waste involved, and furthermore, during said waste and leakage, the motive fluid is permitted to pass to the piston of the tool, frequently causing the latter to accidentally 75 start or fly out of the cylinder, together with the bushing or river set, which may cause serious injury. It will be readily seen that all these dangers and disadvantages are 80 prevented by my device. 85

I desire also to call especial attention to the advantages of my novel construction whereby springs are dispensed with, it being understood that owing to the slight play of .005 between the piston 13 and the lower portion of its bushing, there is constant air pressure always leaking past said piston below it, so as to always press the valve 14 upwardly against its seat. 90

I have found this construction in practice to be very advantageous, since it not only lessens the cost of manufacture, but, in addition, makes the throttle valve easier to operate, since the workman's thumb can depress the lever 23 more comfortably against the cushion of live motive fluid, than against a spring, as heretofore generally employed. 95

It will now be apparent that I have devised a novel and useful construction of a pneumatic tool handle, which embodies the 105 features of advantage enumerated as desirable in the statement of the invention and the above description, and while I have, in the present instance, shown and described a preferred embodiment thereof which will 110 give in practice satisfactory and reliable results, it is to be understood that the same is susceptible of modification in various particulars without departing from the spirit or scope of the invention or sacrificing 115 any of its advantages.

Having thus described my invention, what I claim as new and desire to secure by Letters Patent, is:—

The combination of a pneumatic tool handle having an inlet chamber located at the lower outer portion of said handle and a pressure supply duct leading through the grasping portion thereof, a manually operated valve lever pivotally mounted in a narrow slit in the upper portion of said handle and capable of a free and uninterrupted forward movement, a throttle valve bushing extending entirely through said handle and having an upper bore and a lower bore 120 125 130

therein of greater diameter, a single closure secured within the bottom of said bushing, a downwardly facing valve seat being formed at the junction of said bores, and 5 said bushing having an inlet port constantly open to motive fluid in said lower bore and a lateral outlet port in its upper bore respectively, a throttle valve seating upwardly against said seat, the body of said valve extending below said seat, and fitted in said bushing with a play of about .005 of an inch to permit motive fluid to leak through said constantly open inlet port against said valve body and be withdrawn downwardly past 10 said valve to the bottom thereof, so as to constantly press said valve upwardly against

its seat, the space between said closure and the bottom of said valve being unobstructed, a valve stem extending above and integral with said throttle valve, a piston on said valve stem of less diameter than said valve and having a ground fit within said upper bore of said bushing, said piston and valve stem being connected to said valve body and adapted to reciprocate in unison therewith, 20 and a cam on said valve lever in direct contact with the top of said valve stem to depress the latter.
